(57) **CLAIM**

The ornamental design for a vehicle wheel hub cover, as shown and described.

DESCRIPTION

FIG. 1 is a front perspective view of a vehicle wheel hub cover;

FIG. 2 is a back perspective view of a vehicle wheel hub cover of FIG. 1;

FIG. 3 is a bottom view of a vehicle wheel hub cover of FIG. 1;

FIG. 4 is a top view of a vehicle wheel hub cover of FIG. 1;

FIG. 5 is a left side elevational view of a vehicle wheel hub cover of FIG. 1;

FIG. 6 is a right side elevational view of a vehicle wheel hub cover of FIG. 1;

FIG. 7 is a front elevational view of a vehicle wheel hub cover of FIG. 1;

FIG. 8 is a rear elevational view of the vehicle wheel hub cover of FIG. 1;

FIG. 9 is a cross-sectional view of a vehicle wheel hub cover of FIG. 1, sectioned along line 9-9 in FIG. 7;

FIG. 10 is a cross-sectional view of a vehicle wheel hub cover of FIG. 1, sectioned along line 10-10 in FIG. 7; and, FIG. 11 is an exploded cross-sectional view of a vehicle wheel hub cover of FIG. 1, sectioned along line 10-10 in FIG. 7.

The evenly spaced broken lines depict portions of the vehicle wheel hub cover that form no part of the claimed design. The dash dot dash broken lines depict cross sectional indicators that form no part of the claimed design.

1 Claim, 9 Drawing Sheets
